UNITED STATES PATENT OFFICE

168,720

VEHICLE DIRECTIONAL SIGNAL

John F. Waldman, Enid, Okla.

Application October 16, 1952, Serial No. 21,847

Term of patent 14 years

(Cl. D72—1)

To all whom it may concern:

Be it known that I, John F. Waldman, a citizen of the United States, residing at Enid, in the county of Garfield and State of Oklahoma, have invented a new, original, and ornamental Design for a Vehicle Directional Signal, of which the following is a specification, reference being had to the accompanying drawing, forming part thereof.

Figure 1 is a front perspective view of a vehicle directional signal, showing my new design;

Figure 2 is a front elevational view thereof, and

Figure 3 is a top edge view of the same.

The rear of the signal is conventionally plain.

The drawing is shaded to illustrate contrast of color.

The dominant features of my design are shown in solid lines.

I claim:

The ornamental design for a vehicle directional signal, as shown and described.

JOHN F. WALDMAN.
